PACKAGING MACHINE

Robert William Vergobbi, Quincy, Mass., assignor
to Pneumatic Scale Corporation, Limited,
Quincy, Mass., a corporation of Massachusetts

Application July 26, 1940, Serial No. 347,721

10 Claims. (CL. 93—44.1)

This invention relates to a packaging machine. One object of the invention is to provide a novel and improved packaging machine for closing the bottom flaps of a carton and in which provision is made for registering the carton vertically in order to cause it to assume a predetermined vertical position preparatory to subsequent filling and top closure operations.

Another object of the invention is to provide a novel and improved bottom flap closing mechanism by which the bottom flaps of the carton may be closed in a novel and improved manner. The improved bottom closing mechanism is particularly adapted for use in operation upon cartons composed of relatively thin board.

With these general objects in view, and such others as may hereinafter appear, the invention consists in the packaging machine, and in the various structures, arrangements and combinations of parts hereinafter described and particularly defined in the claims at the end of this specification.

In the drawings illustrating the preferred embodiment of the invention, Fig. 1 is a side elevation of a sufficient portion of a packaging machine, embodying the present invention, to enable it to be understood; Figs. 2, 3 and 4 are perspective views diagrammatically illustrating the successive steps in the operation of the machine for producing the present bottom fold; Fig. 5 is a plan view of the mechanism for relieving the pressure upon one side of the carton during the vertical registration thereof; Fig. 6 is a front elevation of the mechanism shown in Fig. 1; and Fig. 7 is a side elevation similar to Fig. 1, being partly in cross-section and showing the parts in a different position of operation.

In general, the present invention contemplates a packaging machine of the type wherein a plurality of cartons are arranged to be supported by carton holding pockets mounted upon a carrier and with top and bottom flaps of the carton extending beyond the top and bottom respectively of the pocket. In order to insure satisfactory operation of the entire machine, provision is made for registering the cartons vertically with relation to their pockets in order to cause the cartons to assume a predetermined vertical position, and in the preferred embodiment of the invention, this vertical registration is effected by bottom flap folding mechanism of novel and improved structure and operation. Provision is also made for relieving the pressure or friction of the pocket with relation to the carton at the time of the vertical registration of the carton, a fea-

ture which facilitates operation upon those cartons composed of a relatively light weight board.

Referring now to the drawings, in general, the invention has been illustrated as embodied in a packaging machine having provision for forming, filling and closing the carton, only sufficient portions of such a machine being herein illustrated as will enable the invention to be understood. The illustrated packaging machine is provided with a 5 rotatable disk 10 having a plurality of pockets or carriers 12 mounted thereon in which the cartons 14 are supported. The rotatable disk 10 is adapted to be intermittently rotated to present the cartons into operative position with relation 10 to the various instrumentalities forming part of the packaging machine for performing the bottom closing, filling, top closing and sealing operations to produce a complete filled and sealed package.

15 20 In the operation of the packaging machine, previous to arriving at the illustrated device forming the subject matter of the present invention for closing some of the bottom flaps to enable the carton to be filled and for vertically registering the carton in the pockets as above described, the carton is inserted into the pocket 14 in its open or tubular condition, as illustrated, and with its top and bottom flaps extended, as shown. After leaving the present device, where 25 three of the usual four bottom flaps of the carton are closed, the carton is presented to a filling unit to be filled with the material being packaged. During the filling operation, the fourth flap remains in its extended position and thereafter the 30 carton is presented to an adhesive applying station where adhesive is applied to the fourth flap and the flap closed to seal the carton. The top flaps are likewise closed and sealed after the filling operation has been completed. Such mechanisms may comprise any of the usual carton filling and sealing instrumentalities now embodied 35 in commercial packaging machines and have been omitted from the illustrated machine since 40 45 of themselves they form no part of the present invention.

Some of the features of the present invention are particularly adapted for the handling of a carton made up of a relatively thin board stock, 50 which cartons have heretofore been extremely difficult to handle successfully in a high speed packaging machine because of the relatively weak structure of the carton. However, it is not desired to limit the invention in this respect since the present invention may be embodied in a ma-

chine for handling cartons made up from material of a more substantial nature as well.

Referring now to Figs. 1 and 2, it will be observed that the carton 14 is provided with the usual four bottom flaps including end flaps 16, 18, and side flaps 20, 22. In the operation of the machine, the side flap 20 is first folded in to closed position, and in the preferred embodiment of the invention provision is made for binding the end flaps 16, 18 outwardly a distance sufficient to avoid interference with the closure of the side flap 20. As herein shown, the side flap 18 is held in its outwardly moved position by a stationary hook shaped member 24 adjustably supported in a bracket 26 attached to a bar 28 fixed to a stationary part of the machine frame, as shown in Fig. 7. In operation, when the carton is moved into the bottom folding position, the leading flap 16 rides over the stationary member 24, the flap immediately returning to its vertically extended position when it passes beyond the member 24, and as the carton continues to move the rear flap 18 is engaged by the member 24 just before the carton comes to rest so that the flap 18 is held in the position shown in Figs. 2 and 6 during the folding operation.

The leading flap 16 is arranged to be moved outwardly by a cam operated finger 30 which is pivotally mounted upon a stud 32 fixed in the machine frame. A second arm 34 of the finger 30 is connected by a link 36 to one arm 38 of a cam lever 40, the latter carrying a roller 42 in cooperation with a cam 44 fast upon a cam shaft 46 forming a part of the packaging machine.

From the description thus far, it will be observed that the end flaps 16, 18 have been moved outwardly in preparation for folding in the side flap 20, and as herein shown, the flap 20 is arranged to be tucked in by a movable folding plate 50 through connections from a cam 52. In accordance with the present invention the folding plate is also arranged to raise the carton in its pocket in the event that the carton is not properly registered vertically therein. The folding plate 50 is mounted on a link 54 which is pivotally connected at one end to one arm 56 of a two armed lever, and the link 54 is connected at its other end by a link 58 to an arm 60 pivotally mounted on a shaft 62 journaled in suitable bearings in a bracket 64 attached to the machine frame. The arm 56 also is rockingly mounted on the shaft 62 and the second arm 66 of the two armed lever is connected by a link 68 to one arm 70 of a cam lever 72 which carries a roller 74 cooperating with the operating cam 52. As illustrated in Fig. 1, the arms 56, 60 and links 54, 58 are arranged to be rocked as a unit to fold the flap 20 inwardly, the parts being held together in the position shown by a spring 76, one end of which is connected to the plate carrying link 54, and the other end to a stud 78 secured in the arm 56. One end 80 of the stud 78 is arranged to engage a portion 82 of the link 54 to serve as a stop for limiting the movement of the links and to maintain the parts in the position shown in Fig. 1.

In the operation of the device, when the actuating member 56 is rocked in a clockwise direction, viewing Fig. 1, the parts are moved as a unit to tuck in the flap 20, and when the unit has been moved a distance sufficient to dispose the plate 50 in a position substantially parallel to the bottom of the carton, as shown in Fig. 7, the arm 60 is arranged to engage a stop screw 84 secured to a bar 86 attached to the machine frame. With

the parts in this position the pivoted point 88 becomes fixed so that upon further clockwise movement of the actuating member 56 the parts operate as a four-bar linkage to move the folding plate 50 forwardly and upwardly to cause the carton to be raised in the pocket, in the event that such carton is improperly registered therein. It will be observed that during this movement the links 54, 58 rock on their pivots so as to move the parts relative to the arm 56, the spring 76 being extended as shown in Fig. 7.

In order to limit the upward movement of the carton and to register it at a predetermined height with respect to its pocket, a stationary top plate or gauge member 90 is provided, fixed to the machine frame, and against which the top flaps of the carton contact.

Provision is also made in the preferred embodiment of the invention for bending the side flap 22 slightly outwardly in order to permit the end flaps 16, 18 to be folded over in overlapping relation to the side flap 20 during subsequent operations, and as herein shown, an angular plate 92 carried by the link 54 and disposed immediately below the folding plate 50 is arranged to engage the flap 22 and bend it outwardly, as shown in Fig. 7.

In practice, when operating upon cartons made up of relatively thin board stock, such as cardboard of approximately nine-thousandths thickness, for example, it was found that the lower edge of the front panel would have a tendency to buckle during the folding and registering operation above described on account of the relatively weak structure of the carton, thus producing an imperfect bottom fold and improper registration. In order to eliminate such buckling of the carton panel, a yieldingly mounted supporting bar 94 is provided which operates to press against the lower portion 95 of the front panel and to prevent buckling or twisting of the carton during the bottom folding operation. As herein shown, the supporting bar 94 is mounted upon two pins 96, 98 slidably mounted in a supporting member 100 attached to the bar 28. Coil springs 102, 104 are coiled about the pins 96, 98, respectively between the members 94 and 100, and the outer ends of the pins are provided with keys 106 to limit the movement of the bar 94. It will be observed that the forward portion of the bar 94 is curved, see Fig. 5, so as to permit the carton to be moved into yielding engagement with the bar as it is moved into operative position from the preceding station.

Referring now to Fig. 5, it will be observed that one side 108 of the pocket 12 is carried by an arm 109 pivotally mounted at 110 to provide a gate which is opened at the proper time to permit insertion of and removal of the carton during the operation of the packaging machine. In practice, such gate is yieldingly held against the side of the carton in order to retain the same firmly in the pocket, such as by a spring 112. When handling light weight cartons the normal tension of the spring causes the front panel to buckle slightly, as shown at 114 in Fig. 5. In order to relieve the pressure of the gate so as to permit the carton to square itself up and to permit a minimum frictional resistance during the elevating movement of the carton as described, provision is made for rocking the gate slightly and, as herein shown, an arm 116 formed integrally with the gate arm 109 is provided with a roller 118 which is arranged to engage a stationary cam piece 120 just before the pocket

comes to rest at the bottom folding station to open the gate sufficiently to relieve the pressure while still serving to support the carton.

From the description thus far, it will be observed that the flap 20 has been folded in and the carton has been raised bodily in the pocket. Thereafter, in the operation of the machine, provision is made for closing the end flaps 16, 20. As herein shown, see Fig. 6, the end flap 18 is folded over by a folding arm 122 which is rockingly mounted upon the stud 32. A second arm 124 forming part of the folding arm is connected by a link 126 to one arm 128 of a cam lever 130 which is provided with a roller 132 arranged to cooperate with a cam 134 mounted fast upon the cam shaft 46.

In operation, the end flap 18 is not folded in until the carton has started to move to the next station of operation, and in the interim the previously folded flap is held in position by the plate 50. As the carton starts to move, the plate 50 starts to retract still in engagement with the flap 20, this movement of the carton with relation to the folding plate being made possible by the provision of cut-outs 148, 150 in the plates 50, 92. When the flap 18 has ridden over the holding member 24, the folding arm 122 operates to tuck the flap in while the plate 50 is being fully retracted. By this time the remaining flap 16 has been engaged by a stationary rail 136 to fold it in, and in operation the arm 122 continues in engagement with its flap 16 during the movement of the carton until the flap 16 also has been received under the stationary rail 136 to hold the flaps in their closed position in readiness for the filling operation.

From the above description it will be seen that the present bottom folding device is particularly adapted for use in a packaging machine for handling cartons made of relatively thin board stock and that it also serves to register the carton vertically with relation to the pocket in order to cause it to assume a predetermined vertical position preparatory to subsequent filling and closing operations.

While the preferred embodiment of the invention has been herein illustrated and described, it will be understood that the invention may be embodied in other forms within the scope of the following claims.

Having thus described the invention, what is claimed is:

1. In a packaging machine, in combination, a movable carrier provided with a plurality of carton holding pockets, each constructed to hold a carton with top and bottom flaps extended above and below the pockets, a gauge member disposed above the pocket and above the extended top flaps of the carton supported therein, bottom flap folding instrumentalities, and mechanism for adjusting the position of the carton in the pocket to cause the top flaps to engage said gauge member and to cause the carton to be thereby disposed in a predetermined vertical position for subsequent operations to be performed thereon.

2. In a packaging machine, in combination, a movable carrier provided with a plurality of carton holding pockets, each constructed to hold a carton with top and bottom flaps extended above and below the pockets, and means adapted to be moved into engagement with the carton while the latter is held in the pocket for adjusting the position of the carton in the pocket to cause the

carton to assume a predetermined vertical position.

3. In a packaging machine, in combination, a movable carrier provided with a plurality of carton holding pockets, each constructed to hold a carton with top and bottom flaps extended above and below the pockets, means for adjusting the position of the carton in the pocket to cause the carton to assume a predetermined vertical position, said means comprising a bottom flap folding member, and operating means for moving the same and the carton into a predetermined vertical position with respect to the pocket.

15 4. In a packaging machine, in combination, a movable carrier provided with a plurality of carton holding pockets, each constructed to hold a carton with top and bottom flaps extended above and below the pockets, means for adjusting the 20 position of the carton in the pocket to cause the carton to assume a predetermined vertical position, said means comprising a bottom flap folding member for folding inwardly one of the bottom flaps of the carton, and operating mechanism for imparting to the folding member an inward and also a vertical movement.

5. In a packaging machine, in combination, a movable carrier provided with a plurality of carton holding pockets, each constructed to hold a carton with top and bottom flaps extended above and below the pockets, means for adjusting the position of the carton in the pocket to cause the carton to assume a predetermined vertical position, said means comprising a bottom flap folding member for folding inwardly one of the bottom flaps of the carton, and operating mechanism for imparting to the folding member an inward and also a vertical movement, said mechanism including a four bar linkage adapted to move said one flap to its closed position during one portion of its movement and to thereafter engage the bottom edge of the carton to cause the latter to move vertically during the remainder of its operating stroke.

40 6. In a packaging machine, in combination, carton supporting means arranged to support a carton with the bottom flaps extended, and bottom flap folding means comprising a movable folding member provided with one portion for engaging and folding inwardly the first bottom flap of the carton and another portion for folding outwardly the opposing bottom flap of the carton preparatory to the folding inwardly of the two intermediate bottom flaps.

45 7. In a packaging machine, in combination, carton supporting means arranged to support a carton with the bottom flaps extended, and bottom flap folding means comprising a movable folding member provided with one portion for engaging and folding inwardly the first bottom flap of the carton and another portion for folding outwardly the opposing bottom flap of the carton preparatory to the folding inwardly of the two intermediate bottom flaps, and two flap folding members for engaging and holding outwardly the two said intermediate flaps during the folding of the first bottom flap.

50 8. In a packaging machine, in combination, carton supporting means arranged to support a carton with the bottom flaps extended, and bottom flap folding means comprising a flap folding member for folding in the first bottom flap, means for holding outwardly the remaining bottom flaps, and a yieldable support for the lower portion of the side panel of the carton opposite

the panel to which the first folded flap is attached.

9. In a packaging machine, in combination, a carton supporting means arranged to support a carton with the bottom flaps extended, and bottom flap folding means comprising a movable folding member provided with one portion for engaging and folding inwardly the first bottom flap of the carton and another portion for folding outwardly the opposing bottom flap of the carton preparatory to the folding inwardly of the two intermediate bottom flaps, and two flap folding members for engaging and holding outwardly the two said intermediate flaps during the folding of the first bottom flaps, and a yieldable support for the lower portion of the side

panel of the carton opposite the side panel to which the first folded bottom flap is attached.

10. In a packaging machine, in combination, a movable carrier provided with a plurality of carton holding pockets, each constructed to hold a carton with top and bottom flaps extended above and below the pocket, said pocket having one side thereof pivoted to be capable of outward movement, bottom flap folding means, means for adjusting the position of the carton in the pocket to cause it to assume a predetermined vertical position, and cam operated means for moving the pivotal side of the pocket outwardly when the carton is to be moved vertically with relation to the pocket.

ROBERT WILLIAM VERGOBBI.
